(57) **CLAIM**

We claim the ornamental design for a head mounted display, as shown and described.

DESCRIPTION

FIG. 1 is a front perspective view of a first embodiment of a head mounted display of the present invention;
FIG. 2 is a rear perspective view thereof;
FIG. 3 is a front view thereof;
FIG. 4 is a rear view thereof;
FIG. 5 is a first side view thereof;
FIG. 6 is a second side view thereof;
FIG. 7 is a top view thereof;
FIG. 8 is a bottom view thereof;
FIG. 9 is a cross-sectional view taken along the line 9-9 of FIG. 3 with the internal parts being omitted;
FIG. 10 is a cross-sectional view taken along the line 10-10 of FIG. 4 with the internal parts being omitted thereof;
FIG. 11 is an enlarged view of the portion defined by 11-11 of FIG. 2 thereof;
FIG. 12 is a front perspective view of a second embodiment of a head mounted display of the present invention;
FIG. 13 is a rear perspective view thereof;
FIG. 14 is a front view thereof;
FIG. 15 is a rear view thereof;
FIG. 16 is a first side view thereof;
FIG. 17 is a second side view thereof;
FIG. 18 is a top view thereof;
FIG. 19 is a bottom view thereof;
FIG. 20 is a cross-sectional view taken along the line 20-20 of FIG. 14 with the internal parts being omitted thereof;
FIG. 21 is a cross-sectional view taken along the line 21-21 of FIG. 15 with the internal parts being omitted thereof; and,
FIG. 22 is an enlarged view of the portion defined by 22-22 of FIG. 13 thereof.

The evenly spaced broken lines represent portions of the head mounted display that form no part of the claimed design.
